CLAIM

The ornamental design for an electronic cigarette, as shown and described.

DESCRIPTION

FIG. 1.1 is a perspective view of an electronic cigarette, according to a first embodiment of our new design;

FIG. 1.2 is a front view thereof;

FIG. 1.3 is a rear view thereof;

FIG. 1.4 is a left side view thereof;

FIG. 1.5 is a right side view thereof;

FIG. 1.6 is a top view thereof;

FIG. 1.7 is a bottom view thereof;

FIG. 2.1 is a perspective view of an electronic cigarette, according to a second embodiment of our new design;

FIG. 2.2 is a front view thereof;

FIG. 2.3 is a rear view thereof;

FIG. 2.4 is a left side view thereof;

FIG. 2.5 is a right side view thereof;

FIG. 2.6 is a top view thereof;

FIG. 2.7 is a bottom view thereof;

FIG. 3.1 is a perspective view of an electronic cigarette, according to a third embodiment of our new design;

FIG. 3.2 is a front view thereof;

FIG. 3.3 is a rear view thereof;

FIG. 3.4 is a left side view thereof;

FIG. 3.5 is a right side view thereof;

FIG. 3.6 is a top view thereof;

FIG. 3.7 is a bottom view thereof;

(Continued)

FIG. 4.1 is a perspective view of an electronic cigarette, according to a fourth embodiment of our new design;
 FIG. 4.2 is a front view thereof;
 FIG. 4.3 is a rear view thereof;
 FIG. 4.4 is a left side view thereof;
 FIG. 4.5 is a right side view thereof;
 FIG. 4.6 is a top view thereof;
 FIG. 4.7 is a bottom view thereof;
 FIG. 5.1 is a perspective view of an electronic cigarette, according to a fifth embodiment of our new design;
 FIG. 5.2 is a front view thereof;
 FIG. 5.3 is a rear view thereof;
 FIG. 5.4 is a left side view thereof;
 FIG. 5.5 is a right side view thereof;
 FIG. 5.6 is a top view thereof;
 FIG. 5.7 is a bottom view thereof;
 FIG. 6.1 is a perspective view of an electronic cigarette, according to a sixth embodiment of our new design;
 FIG. 6.2 is a front view thereof;
 FIG. 6.3 is a rear view thereof;
 FIG. 6.4 is a left side view thereof;
 FIG. 6.5 is a right side view thereof;
 FIG. 6.6 is a top view thereof;
 FIG. 6.7 is a bottom view thereof;
 FIG. 13.1 is a perspective view of an electronic cigarette, according to a seventh embodiment of our new design;
 FIG. 13.2 is a front view thereof;
 FIG. 13.3 is a rear view thereof;
 FIG. 13.4 is a left side view thereof;
 FIG. 13.5 is a right side view thereof;
 FIG. 13.6 is a top view thereof;
 FIG. 13.7 is a bottom view thereof;
 FIG. 14.1 is a perspective view of an electronic cigarette, according to an eighth embodiment of our new design;
 FIG. 14.2 is a front view thereof;
 FIG. 14.3 is a rear view thereof;
 FIG. 14.4 is a left side view thereof;
 FIG. 14.5 is a right side view thereof;
 FIG. 14.6 is a top view thereof;
 FIG. 14.7 is a bottom view thereof;
 FIG. 22.1 is a perspective view of an electronic cigarette, according to a ninth embodiment of our new design;
 FIG. 22.2 is a front view thereof;
 FIG. 22.3 is a rear view thereof;
 FIG. 22.4 is a left side view thereof;
 FIG. 22.5 is a top view thereof;
 FIG. 23.1 is a perspective view of an electronic cigarette, according to a tenth embodiment of our new design;
 FIG. 23.2 is a front view thereof;
 FIG. 23.3 is a rear view thereof;
 FIG. 23.4 is a left side view thereof;
 FIG. 23.5 is a top view thereof;
 FIG. 24.1 is a perspective view of an electronic cigarette, according to an eleventh embodiment of our new design;
 FIG. 24.2 is a front view thereof;
 FIG. 24.3 is a rear view thereof;
 FIG. 24.4 is a left side view thereof;
 FIG. 24.5 is a top view thereof;
 FIG. 25.1 is a front view of an electronic cigarette, according to a twelfth embodiment of our new design;
 FIG. 25.2 is a rear view thereof;
 FIG. 26.1 is a perspective view of an electronic cigarette, according to a thirteenth embodiment of our new design;

FIG. 26.2 is another perspective view thereof;
 FIG. 27.1 is a perspective view of an electronic cigarette, according to a fourteenth embodiment of our new design;
 FIG. 27.2 is another perspective view thereof;
 FIG. 28.1 is a perspective view of an electronic cigarette, according to a fifteenth embodiment of our new design;
 FIG. 28.2 is another perspective view thereof;
 FIG. 29.1 is a front view of an electronic cigarette, according to a sixteenth embodiment of our new design;
 FIG. 29.2 is a rear view thereof;
 FIG. 30.1 is a front view of an electronic cigarette, according to a seventeenth embodiment of our new design;
 FIG. 30.2 is a rear view thereof;
 FIG. 31.1 is a front view of an electronic cigarette, according to an eighteenth embodiment of our new design;
 FIG. 31.2 is a rear view thereof;
 FIG. 32.1 is a front view of an electronic cigarette, according to a nineteenth embodiment of our new design; and
 FIG. 32.2 is a rear view thereof.
